SAMUEL F. HILTON, OF PROVIDENCE, RHODE ISLAND.

Design No. 4,277, dated August 9, 1870.

DESIGN FOR A COLLAR-BOX.

The Schedule referred to in these Letters Patent and making part of the same

I, SAMUEL F. HILTON, of the city and county of Providence, and State of Rhode Island, have invented and produced a new and original Design for a Collar-box, for containing collars in a merchantable package, of which the following is a specification.

The nature of my design is that of a clock, the dial of which occupies one face of the box, which may be colored or ornamented, to more fully represent a clock in appearance.

Said design is fully represented in the accompanying drawing, to which reference is made.

Claim.

I claim as my invention—
The design for a collar-box, as shown and specified.
